UNITED STATES PATENT OFFICE

2,131,567

REVERSIBLE LOCK SLIDER

Davis Marinsky, Bronx, N. Y., assignor to White-hall Patents Corporation, New York, N. Y., a corporation of New York

Application November 18, 1936, Serial No. 111,366

6 Claims. (Cl. 24—205)

This invention relates to separable fasteners and particularly to the sliders for devices of this class; and the object of the invention is to provide a reversible lock slider having means for retaining the slider against upward movement on vertically arranged stringers to prevent opening of the stringers from the lower end thereof, especially in applying devices of the kind under consideration to leggings and other articles of apparel and other merchandise normally arranged in the position stated; a further object being to provide a locking or retaining means constituting part of the finger piece or pull of the slider and consisting of two fingers or pawls, one adapted to enter the channel of the slider to engage one or more of the links of a fastener stringer and the other cooperating with the slider to retain the pull against accidental displacement from its locked position; and with these and other objects in view, the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a perspective view diagrammatically illustrating one use of my invention.

Fig. 2 is a longitudinal sectional view through the lower end portion of the fastener shown in Fig. 1 on an enlarged scale, the section being on the line 2—2 of said figure.

Fig. 3 is a face view of the structure shown in Fig. 2 with parts in a different position and in section.

Fig. 4 is a partial section on the line 4—4 of Fig. 2; and,

Fig. 5 is a view similar to Fig. 3 showing only a part of the construction and showing a modification.

In leggings and other articles of apparel as well as articles of merchandise which open from the lower end of a vertical arrangement of the fastener, it is desirable to retain the slider against upward movement on the stringers, or, in other words, to prevent the stringers from opening, especially where the stringer lower ends are subjected to stress tending to open the same.

To illustrate one use of my invention, I have diagrammatically shown at 5 in Fig. 1 of the drawing a legging or one leg end of a garment of any kind or class, such for example as children's snow suits, ski suits, running trousers and the like. At 6, I have indicated a separable fastener having a slider 7 to open the garment part 5 from the lower foot end portion 8 thereof to

any desired point upwardly of the leg of the garment as indicated at 9.

The separable fastener 6 consists, as is customary, of mounting tapes or side portions 10 and 11, preferably provided with beaded edges 10a, 11a, to which are secured the coupling links or scoops 12 and 12a which are adapted to be coupled and interlocked by the slider 7 movable longitudinally thereof. It is also customary to provide a finger piece or pull 13 for the slider, by 10 means of which the same may be operated to open and close the fastener. The slider 7 has the usual narrow or contracted end portion 14 and the wider or flared end portion 15, the latter having channels which are subdivided by a substantially V-shaped web 16, the channels converging into one channel 17 at the narrow end 14 of the slider.

One side wall, preferably the outer side wall, of the slider 7 is provided with a projecting lug 18 apertured to receive a pivot pin 19 for pivotally mounting the finger piece or pull 13 in connection with the slider, the pivoted end of the finger piece being fork-shaped or yoke-shaped in form. A lock pin or pawl 20 is disposed adjacent the pivoted end of the finger piece or pull and is adapted to extend through an aperture 21 formed in the wall of the slider 7 so as to enter the channel 17 to engage one or more of the links 12, 12a of the fastener stringers 10, 11, depending entirely upon which side of the finger piece or pull the pawl 20 is arranged, it being understood at this time that, if desired, two of the pins or pawls 20 may be provided to engage the links of both stringers.

In spaced relation to the pin or pawl 20, the finger piece or pull 13 is provided with a lock finger or pawl 22, somewhat hook-shaped in form and which is adapted to frictionally pass over the rounded end portion 23 of the web 16 and to enter a recess or depression 24 formed in the outer or lower surface of said web as clearly seen in Fig. 2 of the drawing. When in this position, the finger piece or pull 13 is positively retained against accidental displacement when in its locked position so as to prevent movement of the finger piece or pull, especially in normal uses of the device, it being understood, however, that the finger piece or pull 13 may be forcibly disengaged from its locked position and swung into the dotted line position shown in Figs. 2 and 4 and the full line position indicated in Fig. 3 in the operation of moving the slider longitudinally of the stringers to open and close the same. In the last named position of the pull, the pin or pawl 20 is out of engagement with the channel 17 as well as the links of the fastener stringers.

In Fig. 5 of the drawing, I have shown another form of construction which consists primarily in changing the position of the finger or pawl 22 on

the finger piece or pull. In this figure, I have indicated at 13a a finger piece or pull similar to that shown in the other figures, except that I have substituted for the member 22, a similar 5 hook-shaped member 25 arranged at one side edge of the pull 13a, preferably the edge opposed to that provided with the pin or pawl 20a adjacent the pivot 19a. The finger or pawl 25 is adapted to frictionally pass over the rear edge 26 of the top 10 plate of the slider 7a, and preferably in such position as to register with or pass between two of the links 12 of the stringer, whereas, the pin 20a is adapted to be arranged between the links 12a of the opposed stringer at a point in longitudinally 15 spaced relation to the engagement of the finger 25 with the links 12. With this construction, in addition to securely retain the pull 13a in its locked or operative position, the finger or pawl 25 also serves as additional means for securing 20 the slider against movement on the stringers.

In the accompanying drawing, the slider 7 as well as the finger piece or pull 13 are represented as die cast or molded parts, but my invention is not limited in this respect nor to the particular 25 arrangement of pawls or locking elements employed.

It is desirable that the locking finger or pawl have what might be termed a camming or wedging action in order to be firmly and securely held 30 in operative position. This type of slider may be used in any form or use of separable fastener by adapting the slider and finger piece to the distinct uses.

Having fully described my invention, what I 35 claim as new and desire to secure by Letters Patent, is:

1. In separable fasteners employing stringers having interengaging coupling links, a slider movable longitudinally of the stringers to couple and uncouple said links, said slider having a contracted end portion and a wide flared end portion, a lock element pivoted to the slider inwardly of the end portions thereof, said element comprising a finger piece or pull having a lock pin adjacent 45 the pivoted end thereof, the slider having an aperture through which said pin passes in engaging one of the stringer links to retain the slider against movement longitudinally of the stringers in one direction, and means on the pull outwardly 50 of said pin for engaging the wide end portion of the slider to retain the pull in locked position against accidental displacement.

2. In separable fasteners employing stringers having interengaging coupling links, a slider movable longitudinally of the stringers to couple and uncouple said links, said slider having a contracted end portion and a wide flared end portion, a lock element pivoted to the slider inwardly of the end portions thereof, said element comprising a finger piece or pull having a lock pin adjacent the pivoted end thereof, the slider having an aperture through which said pin passes in engaging one of the stringer links to retain the slider against movement longitudinally of the stringers in one direction, means on the pull outwardly of said pin for engaging the wide end portion of the slider to retain the pull in locked position against accidental displacement, and said means comprising a hook-shaped pawl projecting from one side surface of the pull.

3. A reversible lock slider for separable fastener stringers, said slider comprising spaced plates forming a channeled body having a wide diverging

end portion and a contracted end portion, the plates being joined by a connecting web centrally of the wide end portion thereof, one of said plates having a bearing portion intermediate its ends, a pull movably mounted in said bearing portion, said plate having an aperture at one side of said bearing portion, a lock pin on the pull adapted to pass through said aperture to enter the channel of said body to engage one of the stringers to retain the slider against movement thereon in one direction, said plate joining the outer surface of said web in a rounded corner, the outer surface of the web inwardly of the outer surface of said plate being recessed and a projecting member on said pull adapted to enter the recess in said web 10 to retain the pull against movement on the slider when said pin is in operative position.

4. In combination with a slider for separable fastener stringers, said slider having wide and narrow end portions, of a finger piece or pull pivotally supported on a projection inwardly of the wide end of said slider, and by means of which the slider may be operated longitudinally of the stringers, means adjacent the free end portion of the finger piece or pull adapted to engage the said 20 wide end of the slider to support the finger piece or pull against accidental displacement with respect to said slider, said wide end having a rounded cam surface adjacent a recess formed therein, and said last named means comprising a hook-shaped member adapted to forcibly pass over the cam surface of the wide end of the slider and enter the recess therein in retaining said parts against relative movement.

5. A lock slider for separable fastener stringers, 35 said slider consisting of a channelled body having diverging channels at one wide end connecting with a single channel at the contracted or narrow end thereof, and means movably supported in connection with the slider inwardly of said ends 40 for retaining the slider against movement longitudinally of the stringers, said means comprising a member having a stop pin or pawl passing through the slider and engaging one of the stringers to retain the slider against movement thereon, 45 and another projection engaging the wide end of said slider to retain said member against movement relatively thereto when in locked position, and said last named projection being arranged in the path of one of said stringers and aiding in 50 retaining the slider against movement longitudinally of said stringers.

6. The combination with a slider for separable fastener stringers, said slider having wide and narrow end portions, a finger piece or pull for 55 moving the slider longitudinally of the stringers, means for coupling one end portion of the finger piece or pull to said slider inwardly of the wide end of said slider, a portion of the pull having a projection adapted to pass through the slider to 60 engage one of the fastener stringers, another projection on said pull in longitudinally spaced relation to the first named projection adapted to engage one of said stringers and to engage the wide end of the slider to retain the pull against 65 accidental displacement therefrom, said projections being arranged on one surface and at opposite side edges of the pull and adapted to collectively engage opposed stringers to provide independent keying or locking of the slider with respect to both stringers of the fastener.

DAVIS MARINSKY.
